his Atty.

UNITED STATES PATENT OFFICE.

JOHN H. COOK, OF WASHINGTON, DISTRICT OF COLUMBIA.

COMBINATION-TONGS.

SPECIFICATION forming part of Letters Patent No. 398,129, dated February 19, 1889.

Application filed February 23, 1888. Serial No. 264,902. (No model.)

To all whom it may concern:

Be it known that I, JOHN H. COOK, of Washington, in the District of Columbia, have invented certain new and useful Improvements 5 in Combination-Tongs, of which the following is a specification.

My invention has reference to combination-tongs for removing stove-lids and shaking the stoves, but designed more particularly for removing blowers from grates or open fire-places; 10 and it consists of a novel construction of the same, as hereinafter set forth.

In the drawings, Figure 1 is a perspective view of a pair of tongs embodying my invention; Figs. 2 and 3, detail views of the same; Fig. 4, a view illustrating the invention in its preferred form, and Fig. 5 an end view of the same.

The tongs comprise a pair of levers or arms, 20 A A, which may be pivoted to a handle, B, as shown in Fig. 1, or pivoted to and crossing each other, and each provided with a separate handle, as shown in Fig. 4.

At or near the free ends of the levers A, I 25 provide each of the said levers with a laterally-extending U-shaped arm, C, which will advisably be flattened, so as to present a somewhat extended or flat bearing-face, which shall be at right angles to the levers A, as clearly shown.

Beyond the lateral arms C the levers are each provided with an extension, D, which may be furnished with meshing teeth *a* on their opposing faces, as shown in Fig. 3, so as 35 to enable the tongs to more readily grasp pieces of wood or coal when it is desired to use them for that purpose, or provided with angular notches *d*, as shown in Figs. 4 and 5, to fit upon the stem or axle of the grate, and 40 be thereby used as a shaker.

The laterally-extending arms C are adapted to clasp opposite edges of the handle of the

blower, which is shown in dotted lines in Fig. 4. Where the levers cross each other at a point between their ends, as illustrated in Fig. 45 4, one of the extensions D will advisably, though not necessarily, be omitted and the remaining arm or extension formed so as to serve as a lid-lifter, as also shown in said figure.

The levers may be made of wrought-iron or 50 malleable cast-iron, as may be preferred, and may be rendered more or less ornamental in appearance.

The blower at times becomes quite hot, and it will be seen that by the use of the tongs 55 herein shown and described it may be removed without burning or scorching the hands, and avoids also the liability of the clothing catching fire.

By flattening the arms C, I am enabled to 60 get a firm bearing upon the handle of the blower and prevent the blower from tipping or rocking within the said arms.

I am aware that pipe-tongs and various other and analogous devices have had their 65 jaws extended laterally, and of course to such devices I make no claim.

Having thus described my invention, what I claim is—

1. The tongs herein described, comprising a 70 pair of pivoted levers, each having a lateral U-shaped arm near its end and an extension, D, beyond the lateral arms provided with teeth or notches.

2. The tongs herein described, comprising 75 the pivoted levers A A, provided with the U-shaped arms C C, one of said arms being provided with a curved arm or extension, D.

In witness whereof I hereunto set my hand in the presence of two witnesses.

JOHN H. COOK.
